UNITED STATES PATENT OFFICE.

JOHN F. SENTER, OF TACOMA, WASHINGTON, ASSIGNOR TO JOHN F. RICHARDS, OF TACOMA, WASHINGTON.

ANTICREEPING DEVICE FOR RAILWAY-RAILS.

1,182,806.

Specification of Letters Patent.

Patented May 9, 1916.

Application filed October 4, 1915. Serial No. 54,049.

To all whom it may concern:

Be it known that I, JOHN F. SENTER, a citizen of the United States, residing at Tacoma, in the county of Pierce and State 5 of Washington, have invented a new and useful Anticreeping Device for Railway-Rails, of which the following is a specification.

This invention has reference to anti-10 creeping devices for railway rails, and its object is to provide a device which may be attached to a rail in such manner as to engage a tie and thereby prevent creeping of the rail.

15 In accordance with the present invention there is provided a plate-like structure with means for clamping it to the rail by engagement of the structure with the basic flange of the rail on opposite sides of the 20 web.

On double track roads the rails of one track have a tendency to creep in one direction and those of the other track to creep in the other direction, wherefore a device 25 preventing creeping in one direction is sufficient. In single track roads or where the traffic is in both directions, provision must be made for preventing the creeping of the track in either direction.

30 In accordance with the present invention there is provided a device which will prevent the track from creeping in one direction, or by a slight modification of a portion of the structure the track is prevented 35 from creeping in either direction. However, the structure preventing the creeping of the track in one direction only is more readily attached to the rail and is consequently advantageous for use in connection 40 with double track roads.

Since the anti-creeping device must withstand heavy strains and the rail and anti-creeping device must be fastened together in a permanent manner, although readily 45 releasable one from the other at will, the present invention contemplates means for securing the anti-creeping device and rail together which will embed in the basic flange of the rail to an extent to overcome 50 all tendency of movement of the rail and anti-creeping device one on the other.

The invention will be best understood from a consideration of the following detailed description, taken in connection with

the accompanying drawings forming part 55 of this specification, with the further understanding that while the drawings show a practical form of the invention, the latter is not confined to any strict conformity with the showing of the drawings, but may be 60 changed and modified so long as such changes and modifications come within the scope of the appended claims.

In the drawings: Figure 1 is a cross-section of a rail showing the anti-creeping device in elevation and in operative relation to the rail. Fig. 2 is a plan view of the structure of Fig. 1 showing the relation of the anti-creeping device to a tie, with the rail indicated in dotted lines and the locking member of the anti-creeping device partly in section. Fig. 3 is a bottom plan view of the anti-creeping device structure shown in Fig. 2. Fig. 4 is a section on the line 4-4 of Fig. 2 with the rail in place. 70 Fig. 5 is a perspective view of a gripping block forming part of the anti-creeping device. Fig. 6 is a vertical cross-section through another form of anti-creeping device applied to the rail. Fig. 7 is a plan 80 view of the structure shown in Fig. 6 with the rail omitted and a portion of the gripping block housing in section.

The structure of Figs. 1 to 5 is that of one form of gripping device, while the structure of Figs. 6 and 7 is that of another form of gripping device different in some respects from that of the preceding figures. The gripping device shown in Figs. 6 and 7 is shown and described more in detail and 85 specifically claimed in application No. 30,617, filed by me on May 26, 1915, while the gripping device in its broader aspects is claimed herein, and the structure of Figs. 1 to 5 is specifically claimed herein since it is 90 neither shown nor described in the aforesaid application.

Referring first to Figs. 1 to 5 there is shown a plate-like basic member 1 with a right-side offset 2 near one end having a right-100 angular flange extension 3. In the installed position of the plate 1 the flange 3 is pendant and is extended lengthwise of the plate 1 so as to provide a broad bearing face to engage one side of a tie 4. The end of the 105 plate 1 near the offset 2 is formed with a return bend 5 rising from and overhanging the corresponding end of the plate to consti-

2

tute a laterally extended hook shaped to embrace one long edge of the basic flange 6 of a railway rail 7. The return bend or hook 5 is provided with terminal strengthening flanges 8, curved similarly to the curvature of the hook 5 and continued under the plate 1, considering the plate as in the installed position, while the flange 8 adjacent to the flange 3 merges thereinto. The plate 1 **10** tapers toward the end remote from the hook 5 and on its under face is formed with a longitudinal strengthening web 9 having at one end a continuation 10 joining and strengthening the flange 3. At the narrow **15** end of the plate 1 there is provided a housing 11 rising above the upper surface of the plate 1 and formed with a through passage 12 open at both ends with the passage directed toward the return bend 5 but displaced with respect to the hook 5 toward that side of the plate 1 provided with the offset 2. The passage 12 through the housing 11 is deepened so as to extend a short distance below the upper surface of the plate **20** 1 and the deepened portion of this passage is furthermore prolonged into the plate 1 beyond the housing and toward the hook 5, as indicated at 13. Extending transversely through the housing is another passage 14 with one side, which may be the side toward the hook 5, substantially perpendicular to the length of the passage 12, while the other side tapers in order to accommodate a taper **25** key 15 designed to enter one end of the passage 14 and extend through the other end. Adapted to the passage 12 through the housing 11 is a gripping block 16 shown in Fig. 5 as of generally rectangular form so as to quite snugly fit the passage 12 which may **30** also be of rectangular form. The block 16 is somewhat longer than the housing, so that both ends of the block may be exposed at the corresponding ends of the housing. One end of the block is designed to engage the **35** corresponding edge of the flange 6 of the rail 7 and may, therefore, be termed the jaw end of the block. This jaw end is provided with a series of teeth 17 elongated in a direction up and down of the block when in its **40** installed position and the upper portion of the jaw end is provided with an overhang 18 into which the teeth 17 extend at an acute angle to the first-named portion of the teeth, whereby, as will hereinafter appear, the **45** teeth serve to engage the side edge of the base flange of the rail from top to bottom thereof. As shown the teeth 17 are of triangular cross-section, but, of course, they may be made of any other suitable shape and **50** are of sufficient length to extend entirely across the corresponding edge of the rail flange and above and below it. The block 16 has a transverse passage 19 through it adapted to receive the key 15.

55 The anti-creeping device is applied by

placing the plate 1 underneath the flange of the rail with the hook 15 engaging over the corresponding edge of the flange and then the block 16 is introduced into the housing 11 through that end of the housing remote **60** from the rail. Since the bottom of the passage or channel through the housing is below the level of the bottom of the rail flange in the applied position of the anti-creeping device, the teeth 17 extend below such flange, **65** because the block travels on the bottom of the passage 11. At the same time the overhang or nose 18 of the jaw end of the block 16 is above and in overhanging relation to the corresponding face of the rail flange. **70** Now by delivering one or more blows to that end of the block 16 projecting through the end of the housing remote from the rail the teeth 17 are caused to sink into the edge of the flange of the rail for an appropriate distance. A hammer or sledge may be used for delivering the blows, the block 16 being long enough to provide an accessible end beyond the housing. With the teeth sinking for a distance into the edge of the rail flange **75** there is provided a grip by the gripping block upon the rail flange which is effectively resistant to any creeping tendency of the rail, for when the anti-creeping device is installed the flange 3 is abutted against a **80** suitably placed tie 4 and the latter being lodged in the road ballast constitutes an effective resisting means to the creeping tendency. The wedge key 15 when driven into place effectively locks the block 16 in the **85** housing against any liability of loosening, and as the wedge key may be of slight angle the liability of loosening is reduced to a negligible minimum, although, of course, any suitable means for avoiding even such **90** slight liability may be used. If under any conditions which may arise it becomes desirable to remove the anti-creeping device, it is only necessary to dislodge the key, whereupon but little force is needed to remove the block 16 and so release the anti-creeping device. The rail flange is gripped **95** on opposite sides by the hook 5 and block 16, respectively, and as the nose 18 of the block is in overhanging relation to the rail flange, the anti-creeping device is sustained **100** by the rail. The plate 1 is of a nature to permit its application to the rail with the plate underneath the rail and the flange 3 against the tie at any time and without in **105** any manner disturbing the rail.

110 In Figs. 6 and 7 there is shown a plate 20 of substantially rectangular form and of a width which may be considerably greater than the width of the plate 1 and in fact **115** may be about as wide as a tie. The plate has its under surface formed with ridges 21 which, when the plate is applied to a tie, will bite into the tie, and by making these **120** ridges of herring bone form as shown and **125** 130

described in the aforesaid application liability of splitting the tie is eliminated. At one end the plate 20 has on the surface remote from the ribs 21 a return hook 22 corresponding generally to the hook 5 and for a similar purpose, but the hook 22 may be of less extent lengthwise of the rail than the hook 5. In line with the undercut portion of the hook 22 are stops 23 near opposite sides of the plate 20 and, serving as abutment pieces for the flange of the rail when in entering position with relation to the hook 22. Adjacent to the abutments 23 and also near the other end of the plate 20 are 15 passages 24 through the plate designed to be traversed by railroad spikes, whereby the plate 20 is made fast to a tie with the ribs 21 embedded in the surface of the tie, so that the plate 20 becomes locked to the tie, 20 and, therefore, is able to resist any creeping action of a rail made fast to the plate. In Fig. 6 there is shown a rail 7 with a basic flange 6 like the showing of the other figures. At that end of the plate 20 remote from the 25 hook 22 is a housing 25 provided with a passage 26 lengthwise therethrough and a transverse passage 27 like the passages 12 and 14 of the form shown in Fig. 1 and associated figures. The passage 26 has a deepened 30 portion 28 similar to the deepened extension 13 of the passage 12.

In the structure of Figs. 6 and 7 a key 15 is employed in connection with the housing 25 and a block 16 might be used, but instead 35 of such a block there is provided a block 16^a having a tail piece 29 producing a shoulder 30 where joining the block 16^a. The tail piece 29 takes the place of that part of the block 16 provided with the passage 19 and 40 constitutes a means whereby a hammer blow may be delivered to the block 16^a. The gripping block 16^a has teeth 17^a and a nose end 18^a like the parts 17 and 18 of the gripping block of the preceding figures.

45 A structure such as shown in Figs. 6 and 7 is applied to the top of a tie being there fastened by spikes extending through the holes 24 with the additional fastening means provided for by the ribs 21. The plate 20 with 50 the rail secured thereto in the same manner as in the structure of Fig. 1 and associated figures is proof against creeping of the rail in either direction and is useful in some situations. However, the plate 20 cannot 55 be applied with the ease of the plate 1, since it must be introduced between a rail and an underlying tie. The plate 1 or the plate 20 each with its hook and housing and other structural parts may be a single casting. 60 The gripping blocks 16 or 16^a may each also be a single casting, while the wedge 15 must, of course, be a separate piece. It follows, therefore, that but three pieces are 65 needed and these three pieces when applied to a rail effectively lock thereto against any

liability of the rail creeping with respect to the ties with which the anti-creeping plates engage.

What is claimed is:—

1. In a rail fastening, the plate or support having a fixed jaw at one side for engaging the base flange of a rail, and provided with a guide at the opposite side, and a gripping member movable transversely in the guide, the inner end of said gripping member having teeth which extend vertically from the base of the gripping member and near the top are disposed at an acute angle, forming an overhanging portion which extends over the base flange of a rail, 75 said teeth serving to engage the side edge of the base flange from top to bottom thereof.

2. In a rail fastening, the plate or support having an integral housing provided 85 thereon, said housing being closed at the top and bottom and open at each end, and a gripping member for a rail movable in the housing and of greater length than the same, so as to project at each end therefrom, said gripping member having teeth provided on 90 its inner end to engage with the side edge of the base flange of the rail, the outer extended end of the gripping member being adapted to be struck by a hammer to force 95 the teeth into engagement with the rail, and means provided on the housing to hold the teeth in such engagement.

3. In a rail fastening, the plate or support having an integral housing provided 100 thereon at one side, said housing being closed at the top and sides and open at each end, a recess provided in the top of the plate at the housing, said recess extending inwardly to a point on the plate below the 105 base flange of a rail, when the latter is in place, a gripping member seated in the recess and movable in the housing, and having its inner end formed with teeth to engage with the side edge of the base flange 110 of the rail from the top to the bottom of said edge, and a transverse key extending through the housing and engaging the gripping member to hold it in such engagement.

4. In a rail fastening, the plate or support having a housing formed thereon transversely thereof, said housing being open at both ends, and a gripping member seated 115 on the plate so that its bottom face operates in a lower plane than the bottom of a rail, 120 said gripping member having teeth which are caused to engage the base flange of the rail from top to bottom, and a key co-operating with the housing to hold the gripping member in such engagement.

5. In a rail fastening, a plate or support of a length to extend beneath the basic flange of a rail and beyond both sides thereof, said plate having a hook at one end in the form of a return bend and at the other 130

end provided with a housing open at both ends with the opening through the housing directed toward the hook to one side of the center thereof and with the bottom of the opening through the housing below the top face of the plate on which the housing is formed, and a gripping member adapted to the interior of the housing and provided at one end with teeth adapted to sink into the corresponding edge of the base flange of the rail, the teeth being of greater extent in an up and down direction than the height of the edge of the flange of the rail and extending over and also below the top and bottom edge of the base flange, respectively, said housing having means coacting therewith and with the gripping member to hold the latter in engaged relation to the rail seated on the plate.

6. In a rail fastening, a plate or support of a length to extend beneath the basic flange of a rail and beyond both sides thereof, said plate having a hook at one end in the form of a return bend and at the other end provided with a housing open at both ends with the opening through the housing directed toward the hook to one side of the center thereof and with the bottom of the opening through the housing below the top face of the plate on which the housing is formed, and a gripping member adapted to the interior of the housing and provided at one end with teeth adapted to sink into the corresponding edge of the base flange of the rail, the teeth being of greater extent in an up and down direction than the height of the edge of the flange of the rail and extending over and also below the top and bottom edge of the base flange, respectively.

7. In a rail fastening, a plate or support of a length to extend beneath the basic flange of a rail and beyond both sides thereof, said plate having a hook at one end in the form of a return bend and at the other end provided with a housing open at both ends with the opening through the housing directed toward the hook to one side of the center thereof and with the bottom of the opening through the housing below the top face of the plate on which the housing is formed, and a gripping member adapted to

the interior of the housing and provided at one end with teeth adapted to sink into the corresponding edge of the base flange of the rail, the teeth being of greater extent in an up and down direction than the height of the edge of the flange of the rail and extending over and also below the top and bottom edge of the base flange, respectively, said housing having means coacting therewith and with the gripping member to hold the latter in engaged relation to the rail seated on the plate.

8. In a rail fastening, a plate or support having a fixed jaw at one side for engaging the base flange of a rail, and provided at the opposite side with an integral housing which is closed at the top and bottom and open at each end, the upper face of the plate or support having a transverse recess which leads from the side edge of the plate or support through the bottom of the housing and beyond the inner end of the latter to a point below the base flange of a rail, when the latter is in place, a gripping member for the rail located in the housing and movable in the said recess, said gripping member having teeth on its inner end to engage with the base flange of the rail from top to bottom thereof, the outer end of the gripping member projecting beyond the outer end of the housing so that it may be struck by a hammer to force the teeth into engagement with the rail, and a transverse key extending through the housing and contacting with the gripping member to hold it in such engagement.

In testimony, that I claim the foregoing as my own, I have hereto affixed my signature in the presence of two witnesses.

JOHN F. SENTER.
